United States Patent Office

Des. 191,020
Patented Aug. 1, 1961

191,020

BOAT

Dudley A. Fry, Walnut Creek, Calif.

Filed Apr. 1, 1960, Ser. No. 59,984

Term of patent 14 years

(Cl. D71—1)

FIG-1

FIG-2

FIG-3

FIG-4

Des. 191,020

PAGE 2

FIG-5

FIGURE 1 is a side elevational view of a boat showing my new design, the opposite side thereof being substantially the same.

FIGURE 2 is a bottom plan view.

FIGURE 3 is a front elevational view.

FIGURE 4 is a rear elevational view.

FIGURE 5 is a top plan view.

I claim:

The ornamental design for a boat, as shown and described.
